ATTORNEYS

UNITED STATES PATENT OFFICE.

HAROLD FISHER, OF CHICAGO, AND DIECY HOOBLER, OF STREATOR, ILLINOIS.

MUSIC INSTRUCTOR FOR CHILDREN.

Application filed August 9, 1924. Serial No. 731,164.

To all whom it may concern:

Be it known that we, HAROLD FISHER and DIECY HOOBLER, both citizens of the United States, and residents of Chicago, county of Cook, and State of Illinois, and Streator, county of La Salle, and State of Illinois, respectively, have invented a new and useful Improvement in Music Instructors for Children, of which the following is a full, clear, 10 and exact description.

Our invention relates to improvements in musical instructors for children, and consists in the combinations, constructions, and arrangements herein described and claimed.

15 An object of our invention is to provide a device of the type described by means of which children may become readily acquainted with the relation of the position of the notes upon the staff to the position of 20 the keys upon a piano.

A further object of our invention is to provide a device of the type described by means of which the relationship between the diatonic scale and the keys of the piano are 25 easily made.

30 A further object of our invention is to provide a device of the type described in which a plurality of strips, each representing a note having a predetermined position 35 on a staff are suspended from a common support in such a manner as to permit the movement of the strips relative to one another or the removal of any one or more of the strips at will, thus permitting the arrangement of simple melodies and the like upon the staff. When the device is used in this connection, the various notes of course cannot be suspended immediately above the corresponding keys of the piano.

40 A further object of our invention is to provide a device of the type described which may be placed upon the keys of the piano and removed therefrom at will without in any way damaging or marring the keyboard 45 and adjacent parts.

A further object of our invention is to provide a novel means for designating the relation of the black keys of the keyboard with the white keys.

50 A further object of our invention is to provide a device of the type described which is simple in construction, durable, and thoroughly efficient for the purpose intended.

Other objects and advantages will appear

in the following specification, and the novel 55 features of the invention will be particularly pointed out in the appended claims.

Our invention is illustrated in the accompanying drawings, forming part of this application, in which—

Figure 1 is a front elevation of an embodiment of our invention, in place upon the keyboard of a piano, and

Figure 2 is a sectional view along the line 2—2 of Figure 1.

In carrying out our invention we make use of a pair of upright members 1, parallel, and spaced apart from one another by a pair of parallel horizontal members 2. The members 1 and 2 are preferably constructed of wood and properly finished.

Two horizontally disposed base pieces 3 are fixed at the lower end of the upright members 1 so that the frame so formed may rest upon the white keys 4 of a piano keyboard, (see Figure 1). When the device is so disposed on a keyboard, the frame is in a vertical plane.

A sheet of cardboard 5 is fixed upon the frame so as to lie in front of the horizontally disposed cross pieces 2. This cardboard extends downwardly adjacent to the bottom of the frame, but sufficiently high to clear the black keys 6 of the keyboard, as shown in Figure 1.

The cardboard 5 has imprinted thereupon designs representing tents as shown at 7. Those designs above the groups of two of the black keys 6 are smaller in size than the designs disposed immediately above the 90 groups of three of the black keys 6. This is so that the child may easily distinguish between the groups of black keys.

75 Seven cords 8 to 14 inclusive are stretched between the upright members 1 at equally spaced distances from one another and are parallel with respect to one another. The cords 9 to 13 inclusive are dyed black throughout their length, while the cords 8 and 14 have only a portion intermediate their length dyed black as shown at 16 and 17 respectively. The cords 8 and 14 represent those lines above and below the staff. The cords 9 to 13 inclusive represent the five lines of the staff.

100 A plurality of cardboard strips 20 to 34 inclusive are each provided with a portion 35 at their uppermost end which is turned

back upon the body of the strip so as to permit the strip to be hung upon the upper edge 35 of the cardboard 5, (see Figure 2).

The strips 20 to 27 inclusive have figures 5 thereupon representing notes in the diatonic scale as follows: do, re, mi, fa, sol, la, te, do.

The strip 27 has figures representing C in the diatonic scale on the first line above the staff, that is, in registration with the cord 10 8, and an inscription representing C on the first line below the staff, i. e., the line 14. The figures on the strips 20 to 26 inclusive are in registration with the lines represented by the cords 8 to 12 inclusive, and 15 the spaces between those lines. For other scales these relations are similar, but "do" does not correspond with the eighth and fourteenth lines.

The strips 28 to 34 inclusive have their 20 figures imprinted thereupon representing notes in the diatonic scale from re to do, do being in registration with the space represented by the cords 10 and 11, and immediately above the key C natural of the piano 25 designated at 37.

The strips 20 to 34 inclusive are exactly as wide as the keys 4 of the piano, and the various notes represented by the figures on the strips are disposed immediately above 30 the corresponding keys of the piano, so that a child upon viewing the assembly of figures on the strips, their relationship with the cords 8 to 14 inclusive, and their position relative to one another may easily 35 grasp the relationship between the printed notes on the ordinary musical composition and the keys of the piano.

The black keys of the piano are represented by the tents 7.

In order that children may have a greater 40 interest in the work of becoming acquainted with the relationship of notes upon the staff with the keys of the piano, we have incorporated designs representing notes on the strips 45 20 to 34 inclusive of figures dressed in foot ball regalia, golf costume, etc., three of which are shown in the strips 20 to 22 inclusive. All the strips would have similar figures which would appeal to the eye of 50 the child. In each case the dark portion representing the note proper would be in the form of a cap or hat worn by the figures represented.

A further advantage in the use of our 55 improved musical instructor is that it possesses, in the design of the prints 7, a means for designating the relationship between the black and the white keys of the keyboard.

By the use of our improved musical 60 instructor scales, chords, or any combination of notes used in musical instruction, may be readily visualized by the child or student, and the relationship between the notes thereof with the keys of the piano easily 65 established.

We claim:

1. A musical instructor for children comprising a supporting member arranged to be placed in vertical position upon the keyboard of a piano, cords attached in parallel relation to said keyboard, representing the lines of a musical staff, and removable members adapted for disposition upon said supporting member and arranged to lie in back of said cords, said members having legends imprinted thereon representing notes of a diatonic scale and adapted to lie in registration with one of the cords or spaces between the cords, whereby the members may be moved on said supporting member to a point substantially in registration with the corresponding key of the keyboard.

2. A musical instructor for children comprising a supporting member arranged to be placed in a vertical position upon the keyboard of a piano, cords stretched in parallel relationship with said keyboard representing the lines of a musical staff, means associated with said supporting member and with said cords and keyboard for visibly indicating the relationship between the keys of said keyboard and the position of the corresponding notes on said musical staff, said means comprising a plurality of strips arranged for suspension in a vertical position upon said supporting member, each in registration with a key of said keyboard, said strips having designs printed thereupon representing the notes of a diatonic scale.

3. A musical instructor for children comprising a supporting member arranged to be placed in a vertical position upon the keyboard of a piano, cords stretched in parallel relationship with said keyboard representing the lines of a musical staff, means associated with said supporting member and with said cords and keyboard for visibly indicating the relationship between the keys of said keyboard and the position of the corresponding notes on said musical staff, said means comprising a plurality of strips arranged for suspension in a vertical position upon said supporting member, each in registration with a key of said keyboard, said strips having designs printed thereupon representing the notes of a diatonic scale, said designs being in the form of character figures of particular interest to children, the heads of said figures representing the notes.

4. A musical instructor for children of the character described, comprising a supporting member arranged to be placed upon a piano keyboard, a plurality of parallel horizontally disposed cords stretched across said supporting member, said cords representing the lines of a musical staff, a plurality of strips and means for suspending said vertical strips on said supporting member in registration with the keys of said keyboard,

said strips being provided with designs printed thereupon representing notes of a diatonic scale, and so disposed as to lie in registration with said cords and with the space between said cords.

5. A musical instructor for children of the character described, comprising a supporting member arranged to be placed upon a piano keyboard, a plurality of parallel horizontally disposed cords stretched across said supporting member, said cords representing the lines of a musical staff, a plurality of strips and means for suspending said verti-

cal strips on said supporting member in registration with the keys of said keyboard, 15 said strips being provided with designs printed thereupon representing notes of a diatonic scale, and so disposed as to lie in registration with said cords and with the space between said cords, and means associated with said supporting member for visibly indicating the position of the grouping of the black keys of said piano keyboard.

DIECY HOOBLER.
HAROLD FISHER.
